DESIGN FOR A COMBINED CUP AND SAUCER
DISPLAY STAND

Jack P. Faeder, Beverly Hills, Calif.

Application October 20, 1947, Serial No. 142,037

Term of patent 14 years

(Cl. D80—9)

To all whom it may concern:

Be it known that I, Jack P. Faeder, a citizen of the United States and a resident of the city of Beverly Hills, in the county of Los Angeles, and State of California, have invented a new, original, and ornamental Design for a Combined Cup and Saucer Display Stand, of which the following is a specification, reference being had to the accompanying drawings, forming part thereof, in which:

Fig. 1 is a perspective view of a combined cup and saucer display stand showing my new design;

Fig. 2 is a front, elevational view; and

Fig. 3 is a side, elevational view thereof.

I claim:

The ornamental design for a combined cup and saucer display stand, as shown.

JACK P. FAEDER.
